UNITED STATES PATENT OFFICE.

BENJAMIN F. MAYO, OF SALEM, MASSACHUSETTS, ASSIGNOR TO UNITED SHOE MACHINERY COMPANY, OF PATERSON, NEW JERSEY, A CORPORATION OF NEW JERSEY.

HEEL-TRIMMING MACHINE.

1,104,915.

Specification of Letters Patent. Patented July 28, 1914.

Application filed November 17, 1909. Serial No. 528,554.

To all whom it may concern:

Be it known that I, BENJAMIN F. MAYO, a citizen of the United States, residing at Salem, in the county of Essex and State of Massachusetts, have invented certain Improvements in Heel-Trimming Machines, of which the following description, in connection with the accompanying drawings, is a specification, like reference characters on the drawings indicating like parts in the several figures.

This invention relates to heel-trimming machines and particularly to novel means for supporting and guiding the shoe with relation to the cutter by which the heel is trimmed.

It is customary to employ in heel-trimming machines a toplift guide for engaging the toplift of the heel to determine the extent to which the lower portion of the heel is trimmed, and a rand-guide for engaging the shoe above the heel to determine the extent to which the upper portion of the heel is cut away, this latter guide having a lip formed to enter the rand-crease between the counter portion of the shoe and the heel-seat end of the sole which, for convenience, will herein be included in the term heel.

It is usually desirable to trim a heel so that there is left a substantially uniform projection of the heel-seat all around the heel, although some shoe manufacturers prefer to have the heel trimmed more closely at the sides or breast corners than at the rear end. Certain conditions make it difficult to obtain the desired relative extents of projection of the heel-seat at the rear end and sides of the heel with machines as heretofore constructed. Among these conditions may be mentioned the fact that counters are usually so formed that they present at the sides of the shoe a rounded or bulging guiding surface for engaging the rand-guide. This shape of the guiding surface requires the rand-guide to be positioned very near to the periphery of the cutter in order that the cutter may trim the sides of the heel as closely as is desired. At the back of the shoe the counter usually presents a flatter guiding surface for the rand-guide which, if the rand-guide is positioned the same distance from the periphery of the cutter as is required for trimming the sides of the heel causes the shoe to be guided so close to the cutter that the rear end of the heel is

cut away more than the sides, instead of being cut away to the same extent or to a less extent as it should be. Another condition frequently met is that the sole usually lies closer against the upper at the shank and sides of the heel than it does at the rear end of the heel. This is caused in part by the fact that the sole is usually molded and formed in leveling to present at the shank a convex outer face and, of course, a concave inner face to lie against the upper, while at the rear end of the heel the sole presents an approximately flat face to the upper. The sole thus forms with the upper a relatively narrow rand-crease at the shank and breast corner of the heel and a wide or more open rand-crease at the rear end of the heel. This wider rand-crease at the rear end of the heel allows the shoe pressed against the rand-guide to approach more closely to the periphery of the cutter when the rear end of the heel is being trimmed than when the sides and breast corners are being trimmed. This, of course, causes the rear end of the heel to be cut away more than the sides. A third condition which will be mentioned is that a large portion of the heels are "pitched" forward, that is, they are formed with edge faces inclined to the plane of the toplift, and substantially all such heels have more pitch at the rear end than they have at the sides. This difference in pitch is especially noticeable in the heels of women's shoes. Such heels require to be tilted about that edge of the rand-guide running in the rand-crease as the trimming progresses from a breast corner toward the more pitched rear end. This tilting movement of the shoe carries the heel-seat toward the cutter and causes it to be cut away most where the pitch is greatest. Not only is the heel-seat thus cut away more at the rear end than at the breast corners and sides of the heel, but sometimes in McKay-sewed shoes the line of stitches which secures the sole to the upper and innersole is located so close to the edge of the sole at the heel end, in order to avoid the lasting tacks, that the heel and sole are cut away so much in trimming on a bevel that the stitches are cut and the shoe therefore weakened.

To overcome the difficulties above mentioned, the present invention contemplates providing a heel-trimming machine with means for varying the proximity of the shoe

to the cutter during successive stages of the trimming operation to control the extent to which different portions of the heel are cut away. Said means preferably operates to 5 carry the shoe from the cutter or prevent its approaching the cutter, as the trimming progresses from the breast corner toward the rear end of the heel, and to reversely move the shoe as the trimming progresses 10 from the rear end of the heel toward the other breast corner.

A very important feature of the present invention consists in providing a guiding device for engaging the shoe as it is presented 15 to the cutter, and means for imparting to said device a movement toward or from the periphery of the cutter during the trimming operation. Preferably said means is arranged to give a predetermined movement. 20 By thus moving the guide we control the amount of projection of the heel-seat end of the sole with relation to the counter at all parts of the heel. This movement of the guide toward and from the periphery of the 25 cutter may be sufficient merely to compensate for those conditions which tend to cause the heel to be trimmed unevenly, or it may be great enough to cause the heel to be trimmed less closely at the back than the 30 sides and therefore provide a greater projection of the heel-seat at the rear end of the heel than at the sides and breast corners.

In the machine herein shown, to which this invention has been applied, the heel is 35 supported by its edge on a rest, herein referred to as the edge-rest, and it is found in practice that it is desirable to move the edge-rest vertically with relation to the cutter for supporting the shoe properly while trimming the heel from one breast corner around the rear end of the heel to the other breast corner. As herein shown, a connection is 40 provided between the edge-rest and a guide engaging the counter of the shoe, and hereininafter termed the counter-guide, whereby the guide is automatically moved toward and from the periphery of the cutter in timed 45 relation with the vertical movement of the edge-rest for presenting the shoe in proper position for the sides and rear end of the heel to be trimmed by the cutter. The movement of the edge-rest is effected, as here shown, manually by means of a foot treadle, and a cam plate is connected to the rest and 50 provided with a cam slot receiving the connection with the counter-guide, and having a shape to impart the desired movements to the counter-guide toward and from the periphery of the cutter during the movement 55 of the edge-rest.

It will now be understood that a further important feature of the invention consists in providing a guide for engaging the shoe being trimmed and means for moving said 60 guide toward and from the periphery of the

cutter in timed relation with the trimming of the sides and rear of the heel. In the embodiment of the invention here shown this movement of the guide toward and from the cutter is conveniently effected in timed relation with the movement of the edge-rest with relation to the cutter. The guide and the edge-rest are caused by this means to act together, or in combination, for varying the position of the heel with relation to the cutter. In the construction shown as embodying the invention the edge-rest is connected with the counter-guide so that when the rest is positioned to support the shoe properly for trimming around the rear end of the heel, which, because of conditions present in the shoe as before explained, is liable to be trimmed too closely, said guide will be put into a position farther away from the cutter than when said rest is positioned to support the shoe for the sides of the heel to be trimmed. This movement of the counter-guide determines the extents to which the heel will be cut away on its different sides by the trimmer and so controls the shape of the heel-seat.

In a common type of heel trimming machine, the cutter is composed of a main or heel cutter that trims the main portion of the heel and an auxiliary or rand cutter that trims or bevels the upper portion of the heel seat. Where a cutter of this type is used it is necessary, in order to leave a smoothly trimmed surface to have the movement of the heel take place relative to both the heel cutter and the rand cutter. Accordingly, a further important feature of this invention consists in providing in a machine employing heel and rand cutters, means for effecting a relative movement of the shoe 100 and said cutters for the purpose of controlling the extent to which different portions of the heel are cut away. In the embodiment of the invention shown in the accompanying drawings, this result is effected by having the rand cutter mounted in and movable with the rand-guide, the counter and rand guides both being mounted on a carrier and the counter-guide being movable, as hereinabove described, relative to the rand-guide 110 and rand cutter in a direction transverse to the axis of the rand cutter. The rand-guide is automatically movable longitudinally of the axis of the heel cutter to expose more or less of the width of said cutter, as the height 115 of the heel being trimmed varies, and the arrangement is preferably such that the movements of the rand and counter guides are independent of each other.

Other features of the invention, including 125 certain details of construction and combination of parts, will be hereinafter described and pointed out in the claims.

In the accompanying drawings which show the preferred embodiment of the in- 130

vention, Figure 1 is a plan view of a heel trimming machine embodying this invention; Fig. 2 is a side elevation of the upper portion of the machine shown in Fig. 1; Fig. 3 is a plan view showing the carrier for the rand and counter guides and the mechanism by which these parts are controlled, certain of the parts being shown in section; Fig. 4 is a side elevation showing the heel rest and the cam controlling the counter-guide in the positions that they occupy at the beginning of the trimming operation; Fig. 5 is a side elevation showing the positions of the heel rest and counter-guide controlling cam during the operation of trimming around the rear end of the heel; Fig. 6 is a cross section of the rand cutter, rand-guide and counter-guide, showing their relative positions at the stage of the trimming operation illustrated in Fig. 5; Fig. 7 is a perspective view of the counter-guide and certain parts immediately connected therewith.

Referring now to the drawings, 2 designates a standard which supports at its upper end in suitable bearings 4 a cutter carrying shaft 6. To the shaft 6 is attached a belt pulley 8 and a fly wheel 10. At its left hand end, the shaft 6 carries a rotary heel trimming carrier cutter which comprises a hub 12 and a plurality of adjustable blades 14. Concentric with the path of the cutter blades and attached to a sleeve 15 clamped upon one of the bearings 4 is a toplift guide 16 adapted to receive against it the edge of the toplift of a heel to be trimmed, said guide being formed upon a beveled tread rest 18 also concentric with the path of the cutter blades. Adjustment of the tread rest and the toplift guide toward and away from the path of the cutter may be effected by any suitable means, as for example, by the adjusting screw 20. The face or acting portion of the toplift guide lies substantially parallel with the axis of rotation of the cutter carrying shaft. Attached to the machine head is a casing 22 partially surrounding the heel trimming cutter and to which are attached above and below the cutter suitable guard plates 24 which serve as shields to keep the fingers of the workmen from contact with the cutter.

A rand-guide 26 having a lip 27 to enter the rand-crease, as is best shown in Figs. 3 and 6, is attached to a carrier 28 in any suitable manner, as by screws, the carrier having bosses through which it is connected by bolts 30 and 32 to forked links 34 and 36. The carrier 28 forms a bearing for the hub 38 upon which rand cutter blades 40 are mounted. A link 42 is connected by the universal joint 44 with the main cutter carrying shaft 6 and by a sliding universal joint 46 with the cutter hub 38 and serves to rotate the rand cutter with the heel trimming cutter

while permitting the rand cutter to partake of the movements of the rand-guide and the carrier. The hub 38 is held from longitudinal movement in the carrier 28 by the nut 47 inside the sleeve 48 and therefore the position of the rand cutter with relation to the rand-guide is constant except that the rand cutter rotates.

A channeled arm 50 attached to the machine head at the rear of the parts just described by bolts 51 and extending parallel with the main cutter carrying shaft is provided with grooves in the side wall of its channel in which grooves is slidably mounted a bed piece 52, the bed piece being provided with ribs shaped to fit the grooves in the arm 50. The arm 50 is split and a clamping bolt 54 passing through two parts of the arm is adapted to clamp the bed piece 52 in adjusted position in the channel of said arm. Adjustment of the bed piece 52 relative to the arm 50 is effected through an adjusting bolt 56 threaded through a depending lug upon the bed piece and rotatably confined in a lug attached to the arm 50. It will thus be seen that rotation of the bolt 56 will effect the movement of the bed piece 52 longitudinally of the arm 50 when the clamping bolt 54 is released.

The bed piece 52 is itself provided with grooves in which is received a slide 70, a screw 72, rotatably confined within an ear 74 rising from the bed piece 52 and passing through a screw threaded opening in a lug upon the slide 70, being adapted to effect an adjustment of the slide upon the bed piece. A clamping bolt 78 extends through ears 80 upon the upper side of the bed piece 52 and is arranged to clamp the slide 70 in an adjusted position in the bed piece.

The slide 70 has pivotally connected thereto to one end of the link 36, the link being forked so that it straddles the forward end of the slide, the forked members bearing against bosses upon opposite sides of the slide. A stop 82 adjustably carried by the slide 70 limits the pivotal movement of the link 36 with respect to the slide in one direction. The slide 70 is extended laterally as shown in Figs. 1 and 3, and is provided with a curved slot 84. In this slot is slidably mounted a block 86 having a stud 88 to which the two forked ends of the lever 34 are connected. A spring 90 surrounding one of the bosses upon the slide 70 bears against the link 36 at one end and against one of a series of pins on the slide 70 at its other end and yieldingly holds said link normally against the stop 82 thereby pressing the carrier 28 yieldingly toward the heel trimming cutter. By means of the adjusting devices 56 and 72, with their connecting parts as above described, the link carrying slide 70 and with it the carrier 28 can be adjusted both longitudinally of the

130

cutter shaft and transversely thereof and by means of the adjustable block 86 said carrier can be adjusted to tip the rand guide toward and away from the cutter. The adjustment of the slide 70 determines the position which the edge of the rand-guide shall occupy with relation to the path of the heel trimming cutter when the trimming operation has commenced, it being understood that it is customary to commence the trimming of a heel at the breast corner of the heel. The adjustment of the slide 70 thereby determines the relation which the top of the trimmed heel at the breast corner shall bear to the counter of the shoe.

Located adjacent the rand-guide 26 is a counter-guide 94. The guide 94 is supported by a pair of arms 96 adjustably secured by screws 98, passing through slots in the arms 96, to a yoke 100 sliding in grooves formed in the carrier 28. By means of mechanism to be described, the yoke 100 and the counter guide 94 can be given a movement at the will of the operator in a direction transverse to the axis of the cutter shaft. Pivoted to the yoke 100 by studs 102 is a pair of links 104. Levers 106 having common pivotal connections with the two fork members of the link 36 are connected to the links 104 by pivot pins passing through slots formed near the ends of said links. The other ends of the levers 106 are connected by a long pivot stud 107 and said stud extends through a hole formed in one end of the rod 108. The opposite end of the rod 108 is made hollow to receive one end of a smaller rod 110 and is split as shown in Fig. 1, the split portions being provided with ears through which a clamping bolt extends and by means of which the rod 110 can be adjustably clamped in the rod 108. A rock shaft 112 is suitably supported in the frame of the machine and has rigidly secured thereto an arm 114 which is pivotally connected to the end of the rod 110. Another arm 116 upon the rock shaft 112 is connected to a link or bar 118 provided with a roll 120, said bar being free to be reciprocated longitudinally in a guide 122 fixed with relation to the frame of the machine or with relation to the extension 124 offset therefrom. Said extension is provided with a guideway in which is slidably mounted a plate 126 provided with an irregular cam slot 128 which receives the roll 120.

The plate 126 has jointed to it at 130 a link or rod 132 which is connected at its other end to a treadle 134 pivoted near its middle whereby it may be rocked in either direction by the foot of the operator. The plate 126 carries in a split sleeve or bearing 136 the shank of an edge rest 138, said shank being held adjustably by means of a clamping bolt. By the construction just

described the operator is enabled to move the edge rest 138 either up or down by means of the treadle 134. It will be noted that the bar 118 is confined by its guide 122 against vertical movement with the edge rest, but is permitted to be moved horizontally by the action of the cam slot 128 on the roll 120. Such movement of the bar 118 is transmitted through the mechanism just described to the yoke 100 and counter-guide 94 which are both moved transversely of the axis of the cutter shaft. A helical spring 140 having its ends connected respectively to the link 36 and the upper link 104 tends to maintain the yoke and guide in their positions nearest the carrier 28.

The operation of the hereinbefore described heel trimming machine with this invention applied thereto is as follows: Let it be assumed that the edge rest 138 occupies its normal position, as shown in Fig. 4, with the roll 120 in the upper end of the cam slot 128. In this position the bar 118 will hold the counter guide 94 in its rearmost position and the rand guide 26 will be held by the spring 90 in its position nearest to the circular path in which the blades of the trimming cutter travel in trimming the heel. The heel to be trimmed is laid upon the rest 138 and the edge of the toplift is placed against the toplift guide 16 and the lip of the rand-guide 26 is inserted in the rand-crease of the shoe. In this position the shoe will be guided laterally at three points, namely, at the edge of the toplift, at the rand-crease and at the counter above the heel where it is engaged by the counter guide 94. For the best results the trimming of the heel should be commenced at the corner (see Fig. 4) next the line of the breast with the breast turned upward and the operator should hold the tread face of the heel against the tread rest 18. The cutter rotates in the direction indicated by the arrow in Fig. 4 and it will first attack the heel at the corner of the breast. As the cutter trims, the workman holding the shoe in his hands in the position indicated, raises the rest by rocking the treadle with his foot and at the same time turns the shoe in the direction also indicated by the arrow in Fig. 4. By the time the rear part of the heel arrives in position to be acted on by the cutter the rest 138 will have risen sufficiently to bring the middle of the cam 128 opposite the roll 120. In this position of the plate 126 the bar 118 will have been moved toward the right (as viewed in Fig. 2) far enough to cause the yoke 100, through the intermediate mechanism, to be forced outwardly and hence to move the counter-guide 94 away from the rand-guide 26. Fig. 6 shows substantially the relative positions of the rand cutter, rand-guide and counter-guide at this stage of the trimming operation. It will

now be clear that this movement of the counter-guide shifts that part of the shoe against which the guide acts farther from the path of both the rand and heel cutters. 5 Therefore while the heel may have been trimmed close to or in under the counter at the breast corner, it will be cut away less at the rear end and the desired projection of the heel seat will be left at the rounded end 10 of the heel. If the usual conditions governing the position of the shoe as the trimming progresses from the breast corner toward the rear end of the heel are present, as for example the counter is flatter at the rear 15 end of the heel than at the sides, or the randcrease is more open at the rear end than at the sides so that the heel is permitted to approach closer to the cutter while the rear end is being trimmed, then the movement of 20 the counter-guide away from the cutters will carry the heel away sufficiently to compensate for such variation in the guiding face presented to the cutter. Also if the heel being trimmed has more pitch at the back 25 than at the sides then the movement of the counter-guide away from the cutters will compensate for the movement which the upper end of the heel has toward the cutter when the heel is tipped for keeping the top- 30 lift on the toplift guide. Thus by this invention a heel may be trimmed substantially uniformly all the way around from one breast corner to the other, or it may be cut away to any desired relative extent at its different sides by varying the movements of the 35 counter-guide. In completing the trimming operation from the rear end of the heel to that breast corner opposite the breast corner at which the trimming started, the operator continues to elevate the plate 126 and the rest 40 138, while turning the shoe. By the time the breast corner is reached at which the trimming operation is to stop the roll 120 will have reached the lower end of the cam slot 45 128 and the bar 118 will have been moved toward the left (as seen in Fig. 2) thus allowing the spring 140 to return the counter-guide 94 to its initial position nearest the path of rotation of the cutter blades. The 50 bar 118 is moved by the cam slot 128 and through intermediate parts the counter-guide is moved automatically as the rest sustaining the shoe heel is moved by the operator and the extent of movement of said 55 guide transversely of the axis of the cutter shaft may be varied by changing the shape of the cam 128 in the plate 126. It will therefore be understood that by making the cam slot of the proper shape the heel may 60 be cut away or may be made to project more or less with relation to the counter and more at one part than at another part. It has been stated that it is best to commence the trimming operation at one of the breast 65 corners of the heel, but the particular point

at which the trimming is started is not material to this invention since it will be obvious that the operator may start trimming at any desired point.

Having described my invention, what I 70 claim as new and desire to secure by Letters Patent of the United States is:—

1. In a heel trimming machine the combination with a rotary cutter, of means under the control of the workman movable to vary 75 the position of the shoe during successive stages of the trimming operation, a guide engaging the counter of the shoe being trimmed and means connected with said first mentioned means for moving the guide toward and from the periphery of the cutter in accordance with successive positions of 80 said first mentioned means.

2. In a heel trimming machine the combination with a rotary cutter, of means for 85 moving the shoe into different positions during successive stages of the trimming operation, means for guiding the shoe as it is presented to the cutter and means for effecting in timed relation to the movement of the first 90 mentioned means a relative movement of said guiding means and said cutter in a direction transverse to the axis of the cutter.

3. In a heel trimming machine the combination with a rotary cutter, of a guide for 95 engaging the counter of the shoe as the shoe is presented to the cutter and means for giving said guide varying movements in predetermined succession to cause successive portions of the heel to be cut away to different 100 extents.

4. In a heel trimming machine the combination of a rotary cutter, means arranged to be moved during the trimming operation for supporting a heel at different elevations 105 while the sides and the rear end of the heel are being trimmed and shoe guiding means arranged for movement during the trimming operation in timed relation to the movement of said first named means for guiding the 110 shoe at one distance from the path of the cutter while the rear end is being trimmed and at a different distance while the sides are being trimmed.

5. In a heel trimming machine the combination of a rotary cutter, a heel rest, means under the control of the workman for moving the heel rest vertically, a guide for the shoe and means arranged to give said guide a predetermined movement transversely of 120 the axis of the cutter in timed relation to the movement of the heel rest.

6. In a heel trimming machine the combination of a rotary cutter, a heel rest, means for moving the heel rest vertically, a guide 125 for the shoe and connections between said guide and heel rest for moving said guide toward and from the periphery of the cutter during a portion of the movement of the heel rest and holding said guide against such 130

movement during another portion of the movement of the heel rest.

7. In a heel trimming machine, a cutter, a rand-guide positioned adjacent thereto, and 5 additional means engaging the shoe during the trimming operation and constructed and arranged to move the shoe relatively to the cutter during the trimming operation to cause successive portions of the heel to be 10 cut away to different extents relatively to the counter of the shoe.

8. In a heel trimming machine, the combination with a rotary cutter and a rand-guide for guiding the shoe as it is presented to the 15 cutter, of a device engaging the shoe during the trimming operation and means for imparting to said device varying movements predetermined in extent, direction and succession to cause successive portions of the 20 heel to be cut away to different extents.

9. In a heel trimming machine the combination with a rotary cutter and a rand-guide movable during the trimming operation to expose more or less of the width of the cutter, of a guide engaging the counter of the 25 shoe and means for imparting to said last mentioned guide during the operation of the machine a predetermined movement toward or from the path of the cutter.

30 10. In a heel trimming machine the combination with a heel cutter and a rand cutter, of means constructed and arranged to be actuated in accordance with successive positions of the heel being trimmed to cause a 35 relative movement of the heel and said cutters to control the extent to which different portions of the heel are cut away relatively to the counter of the shoe.

40 11. In a heel trimming machine the combination with a heel cutter and a rand cutter, of means constructed and arranged to be actuated in accordance with successive positions of the heel being trimmed to move the shoe toward or from both of said cutters.

45 12. In a heel trimming machine the combination with heel and rand cutters, of means to move the shoe into different positions during successive stages of the trimming operation, means under control of the operator 50 arranged to be actuated in timed relation to the movement of said means to impart to the shoe a predetermined movement relatively to both of said cutters.

55 13. In a heel trimming machine the combination with a heel cutter and a rand cutter, of a plurality of guiding devices for guiding the shoe as it is presented to the cutter and means for enabling the workman to move one of said guiding devices relatively to both of said cutters during the trimming 60 operation to vary the extent to which different parts of the heel will be cut away relatively to the counter of the shoe.

65 14. In a heel trimming machine the combination with rotary heel and rand cutters,

of a plurality of devices for guiding the shoe as it is presented to said cutters and means for enabling the workman to move one of said guiding devices relatively to both of said cutters and in a direction transverse to the axis of the heel cutter during the trimming operation. 70

15. In a heel trimming machine the combination with a heel cutter, a rand cutter and a rand-guide having a constant guiding 75 relation to said rand cutter, of means for controlling the distance from the rand-guide at which the counter of a shoe can be held during successive stages of the trimming operation. 80

16. In a heel trimming machine the combination of a cutter, a rand-guide, a second guide arranged to engage the shoe and means whereby the second guide may be moved during the trimming operation to 85 vary the position of the shoe relatively to the rand-guide.

17. In a heel trimming machine the combination with a rotary cutter, of means including a rand-guide and a counter-guide 90 for guiding the shoe as it is presented to the cutter, an edge rest and mechanism connecting the edge rest and counter-guide whereby the movements of one of said parts takes place in predetermined relationship to the 95 movements of the other.

18. In a heel trimming machine the combination with rotary heel and rand cutters, a plurality of guiding devices for guiding the shoe as it is presented to said cutters, an 100 edge rest and actuating means for the edge rest, of mechanism connecting the actuating means and one of said guiding devices whereby during the trimming operation said guiding device is moved relatively to both of 105 said cutters and in a direction transverse to the axis of the rand cutter.

19. In a heel trimming machine the combination with a rotary heel trimming cutter, a toplift guide positioned adjacent thereto, 110 a rand cutter and a rand-guide having a constant guiding relation to said rand cutter, of a counter-guide positioned adjacent said rand-guide and means controlled by the operator whereby the counter-guide may be given a to-and-fro movement relatively to the rand-guide during the trimming operation. 115

20. In a heel trimming machine the combination of a rotary cutter, a rand-guide, a 120 counter-guide located adjacent said rand-guide, an edge rest, actuating means for said rest including a cam and means operated by said cam for moving said counter-guide relatively to said rand-guide. 125

21. In a heel trimming machine the combination of a rotary cutter, a rand-guide adjacent said cutter, a carrier supporting said rand-guide, said rand-guide and carrier being automatically movable during the 130

trimming operation as the height of the heel being trimmed varies, a counter-guide also mounted on said carrier, an edge rest, actuating means for said rest including a cam, and 5 mechanism connected with said counter-guide and operated by said cam for moving said counter-guide relatively to said carrier and rand-guide.

In testimony whereof I have signed my name to this specification in the presence of 10 two subscribing witnesses.

Corrections in Letters Patent No. 1,104,915.

It is hereby certified that in Letters Patent No. 1,104,915, granted July 28, 1914, upon the application of Benjamin F. Mayo, of Salem, Massachusetts, for an improvement in "Heel-Trimming Machines," errors appear in the printed specification requiring correction as follows: Page 6, line 70, after the word "cutters" insert the words *during the trimming operation*; same page, lines 71-72, strike out the words "during the trimming operation"; same page, line 94, for the word "takes" read *take*; and that the said Letters Patent should be read with these corrections therein that the same may conform to the record of the case in the Patent Office.

Signed and sealed this 6th day of October, A. D., 1914.

[SEAL.]

R. F. WHITEHEAD,
Acting Commissioner of Patents.
